UNITED STATES PATENT OFFICE

GEORGE M. SCOTT, OF TULSA, OKLAHOMA

PISTON

Original application filed August 14, 1928, Serial No. 299,474. Divided and this application filed July 25, 1929. Serial No. 381,012.

This is a divisional application of the application for patent filed by me August 14, 1928, Serial No. 299,474.

The present invention relates to a piston construction embodying self cooling features.

One of the important objects of the present invention is to provide an improved piston construction adapted particularly for use in connection with air compressors where-
10 in the parts of the piston can be readily and easily assembled or disassembled, without necessitating the entire dismantling of the air compressor, thus saving considerable time and labor.

15 Other objects and advantages of the invention will become apparent during the course of the following detailed description, taken in connection with the accompanying drawings, wherein:

20 Figure 1 is a vertical sectional view through an air compressor illustrating the adaptation of my invention with respect thereto.

Figure 2 is a sectional view, taken approx-
25 imately on the line 2—2 of Figure 1 and looking in the direction of the arrows.

Figure 3 is a sectional view, taken along the line 3—3 of Figure 2, and

30 Figure 4 is an enlarged sectional view through the piston and the adjacent portion of the cylinder showing the manner in which the parts of the piston are assembled.

In the drawings, wherein for the purpose of illustration is shown the preferred embodiment of my invention, the numeral 1 designates generally the supporting base upon which an air compressor structure is mounted, said compressor, in the present instance, comprising a pair of spaced channel rails 2. A base plate 3 is secured across the top of these spaced channel rails by any appropriate fastening means such as is shown at 4, with reference more particularly to Figure 2 of the drawings.

45 The vertically disposed cylinder 5 has its lower end open and resting on the upper face of the central base plate 3, the outer face of the cylinder being provided with spaced cooling fins 6, substantially throughout its
50 length. An elongated cylindrical casing 7

has its lower end encircling the upper portion of the cylinder 5 and the lower end of this casing rests in an angular groove 8 formed in the upper face of an annular collar or shoulder formed on the upper portion 55 of the cylinder 5, as clearly illustrated in Figures 1 and 2.

Upon the upper end of the casing is mounted a circular chamber 15, within one wall of which is journaled a shaft 19 having a pulley 60 wheel or other drive connection 26 mounted on its outer end and with an eccentric 28 carried at its inner end, and to which a piston rod 14 is operatively attached for reciprocating movement within the casing. Operable within the cylinder 5 is a piston 37 which includes a cylindrical body 38, that is open at its upper end to provide an air inlet. The lower portion of the body 38 terminates 65 in the reduced externally threaded head 39 that is formed with a series of spaced air emitting openings 40 that are arranged concentrically with respect to the enlarged central opening 41, as clearly shown in Figures 70 3 and 4 of the drawings.

75 Detachably secured on the reduced externally threaded head 39 of the body 38, is the externally threaded cap 42 whose diameter is substantially the same as the outer diameter of the cylindrical body 38 and the shoulder 42 is formed at the junction of the threads of the cap with the remaining portion of the peripheral portion of the said cap whereby to provide a cooling chamber 43 between the 80 perforated head 39 and the cap 41, as illustrated in Figure 4.

85 The peripheral wall of the cap 41 is formed in its outer face with a ring receiving groove, within which piston rings 44 are 90 fitted. The cylindrical body 38 of the piston 7 is provided with an additional piston ring 45 at the intermediate portion thereof for engagement with the inner face of the sleeve or lining 36, provided for the cylinder 5. 95

100 The body of the piston is furthermore formed with the usual bosses 46 for receiving the pin 47 and a lock screw or other appropriate element 28 is threaded through one of these bosses for engagement with the

wrist pin, whereby to secure the same in position.

The lower end of the connecting rod 14 is detachably associated with a wrist pin enclosing unit designated generally at 49 and which includes a circular head 29 formed with a threaded socket 30, for receiving the end of the connecting rod. A ball bearing assembly 32 is interposed between the circular head 49 and the wrist pin to provide an anti-friction connection between such parts.

The lower end of the connecting rod is provided with a lubricating receiving cavity 51 which is filled up through a suitable opening formed in the side thereof and which opening is normally closed by means of the plug 52. Communication between this cavity 51 and the ball bearing assembly is afforded through the medium of the passage 53, whereby the lubricant may be supplied to the ball bearing.

The cap 41 is formed with an enlarged central threaded opening into which a ring like member 54 is detachably secured, which ring like member has its bottom inner edge bevelled to provide a valve seat 55. A valve stem guide 56 is arranged centrally of the ring 54 and is supported at its lower end on the ring, in any appropriate manner. The upper end of this guide extends inwardly through the central opening 41 formed in the perforated head 39, as clearly illustrated in Figure 4 of the drawings.

A valve stem 57 is slidably disposed through the vertical tubular guide 56 and carried by the lower end of this valve stem is a valve 58 that cooperates with the valve seat 55. A spring retaining member 59 is secured on the upper threaded end of the valve stem 57 for disposition within the reduced rib 39 of the cylindrical body 38, and an expandable coil spring 60 encircles the tubular guide 56, and is disposed between the retaining member 59 and the support for the guide for normally urging the valve stem upwardly to maintain the valve 58 in closed position against the valve seat as shown in Figure 4.

The end of the cylinder 5 is provided with a compression chamber 61. The base plate 3 that provides a closure for the open lower end of the cylinder 5 is formed with a cavity 62 at the juncture of the lower end of the cylinder with the base plate and this detail is more clearly disclosed in Figures 1 and 2 of the drawings. The central portion of the base plate is further formed with an enlarged central opening into which substantially the upper portion of an outlet valve cage 63 and this cage is secured in a rigid manner by a clamping ring 64, that engages with an annular flange 65, formed on the outer wall of the valve cage 63. A suitable post or the like, shown at 66, is disposed through spaced openings formed in the clamping base

and the threaded end of the post are threaded into threaded recesses formed in the bottom face of the base plate 3 around the valve cage.

The valve seat 67 is formed in the upper portion of the valve cage 63, and the valve 68 is normally held in a seated position against the seat 67 by means of the expandable coil spring 69, which encircles the upper portion of the valve stem 70 at the upper end of which is formed or otherwise secured the valve 68. This coil spring engages at its lower end with the guide 71 arranged in the cage for the valve.

The lower open end of the cage 63 has threaded therein the upper end of an elbow 72 and connected with the other end of this elbow is the compressed air discharge pipe 73, extending through an opening 74, formed in the base portion of either or both of the channelled base plate supporting rails 2, as shown in Figure 2.

It will be apparent that during the upward movement of the piston 37 in the cylinder 5, air entering the cylinder at the upper end thereof is forced downwardly through the opening 40 and will enter the cooling chamber 43 through the openings 40, from which chamber it is forced out into the compression chamber 61 when the valve 8 is screwed into an open position by the inrushing air. The rush of air passing through the restricted openings 40 will serve to cool the air and on the down stroke of the piston in the cylinder, the air trapped in the chamber 43 will act as a cooling medium for the piston, while the air in the chamber 61 will be compressed and will be forced out through the valve cage 63, when the valve 68 is moved to an open position by the air under pressure and the compressed air will be discharged out through the pipe 73.

It is obvious as set forth in the specification that various changes may be resorted to without departing from the spirit of the invention or the scope of the appended claims.

What is claimed is:

1. In a piston construction, a cylindrical body open at one end to provide a fluid inlet, the closed end of the cylindrical body being provided with a plurality of fluid emitting openings, a cap arranged on the closed end of the cylindrical body and spaced therefrom to provide a cooling chamber to receive the fluid discharged through said openings, and a valve arranged in the cap to permit the discharge of the fluid from said cooling chamber.

2. In a piston construction, a cylindrical body open at one end to provide a fluid inlet, the other end of said body being reduced to provide a head, said head being provided with a plurality of fluid discharge openings, a cap detachably secured at the reduced head portion and spaced therefrom to provide a

cooling chamber to receive the fluid discharged through said openings, and a spring pressed outlet valve carried by said cap to permit the discharge of fluid from the cooling chamber.

5 In testimony whereof I affix my signature.

GEORGE M. SCOTT.
